CLAIM

The ornamental design for a ladder rung, as shown and described.

DESCRIPTION

FIG. 1 is a perspective view of the ladder rung;
FIG. 2 is a front elevational view of the ladder rung;
FIG. 3 is a top plan view of the ladder rung;
FIG. 4 is a rear elevational view of the ladder rung; and,
FIG. 5 is a side elevational view of the ladder rung, the opposite side being a mirror image thereof.
The bottom of the disclosed ladder rung is unadorned and does not form part of the respective designs.
